DESIGN FOR A NECKLACE

Alfred Philippe, New York, N. Y.

Application February 21, 1939, Serial No. 83,135

Term of patent 3½ years

To all whom it may concern:

Be it known that I, Alfred Philippe, a citizen of the United States of America, residing in city of New York, county of New York, and State of New York, have invented a new, original, and ornamental Design for a Necklace, of which the following is a specification, reference being had to the accompanying drawing, forming part thereof.

Fig. 1 is a plan view of a necklace showing my new design.

Fig. 2 is a developed edge view of the portion between lines A—B of Fig. 1.

I claim:

The ornamental design for a necklace, substantially as shown.

ALFRED PHILIPPE.
